UNITED STATES PATENT OFFICE.

WILLIAM JOHN HEWITT, OF DEL MONTE, CALIFORNIA.

MUFFLER.

SPECIFICATION forming part of Letters Patent No. 771,070, dated September 27, 1904.

Application filed March 22, 1904. Serial No. 199,422. (No model.)

To all whom it may concern:

Be it known that I, WILLIAM JOHN HEWITT, a citizen of the United States, and a resident of Del Monte, in the county of Monterey and State of California, have invented a new and Improved Muffler, of which the following is a full, clear, and exact description.

My invention relates to devices for muffling the exhaust from engines and the like, 10 being particularly adapted for use in connection with explosive-engines. Its principal object is to generally improve the efficiency of such devices.

It consists in the various features and combinations hereinafter described and claimed.

Reference is to be had to the accompanying drawings, forming a part of this specification, in which similar characters of reference indicate corresponding parts in both figures.

Figure 1 is a central vertical longitudinal section through one embodiment of my invention, and Fig. 2 is a side elevation of one of the series of blades.

10 designates a casing, preferably of elongated cylindrical form and having at its opposite ends removable portions or heads 11 11. Near the junctures of the cylindrical with the end portions are provided inlet and outlet pipes or passes 12 and 13, respectively. Ex-

30 tending through the casing is a shaft or supporting member 14, having upon its threaded ends bearing-collars 15, which, with the ends of sleeves 15^a, projecting from the portions 11 11 of the casing, form ways in which operate se-

35 ries of balls 16, permitting the shaft to rotate with but slight resistance. At one end of the shaft, preferably adjacent to the outlet-opening, the thread is continued for a considerable distance at 17, and beyond this thread (here

40 shown as situated near the center of the casing) is a collar or contact member 18, fixed to the shaft. Along the thread 17 a nut or adjustable contact member 19 may move, and between this and the fixed contact member

45 surrounding the shaft are a series of hubs 20, carrying blades or circulating members 21. As illustrated, these blades are in the form of inclined fans and are arranged about the hubs in circular series. The hubs are preferably

50 spaced apart from one another by a plurality

of washers or collars 22, and all these hubs and collars may be forced together to rotate with the shaft by screwing down the nut 19. By varying the number of these spacing-collars the relation and distance between the circulating members may be altered. The blades are revolved by the application of power to a sprocket-wheel 23 or other suitable driving element secured upon one end of the shaft.

55 In the use of my improved muffler the exhaust passes through the inlet-opening into the chamber in the casing between said opening and the circulating members and there expands, losing a portion of its energy. It then impinges against the moving blades, 60 whereby additional force is absorbed, while their revolution produces a suction which tends to draw out the burned gases or the like from the exhaust-valve and considerably decreases the back pressure, thereby increasing 65 the speed of the engine. The exhaust is now discharged through the outlet-passage with hardly audible sound. It will be seen that by creating a draft from the exhaust-passage the efficiency of the engine to which it is applied 70 will be increased and a greatly-enhanced muffling effect obtained by the contact of the exhaust with the moving blades and that this may be adjusted by changing the position of the circulating members. If it is desired, said 75 members may be so positioned upon the shaft that the space between them gradually increases as they approach the outlet, thus giving the gas a better opportunity to expand.

Having thus described my invention, I claim 85 as new and desire to secure by Letters Patent—

1. A muffler comprising a casing provided with inlet and outlet passages, circulating means within the casing, and means for moving said circulating means.

2. A muffler comprising a casing provided with inlet and outlet passages, circulating means within the casing, means for rotating said circulating means.

3. A muffler comprising a casing provided 95 with inlet and outlet passages, a plurality of circulating members movable within the casing, and means for varying the relation between said members.

4. In a muffler, the combination with a cas- 100

- ing provided with inlet and outlet passages, of a shaft extending into the casing, blades mounted upon the shaft, and means for applying power to the shaft to revolve the blades.
- 5 5. In a muffler, the combination with a casing provided with inlet and outlet passages, of a shaft extending into the casing, a circular series of blades mounted upon the shaft, and means for applying power to the shaft 40 to revolve the blades.
- 10 6. In a muffler, the combination with a casing provided with inlet and outlet passages, of a shaft extending into the casing, means for rotating the shaft, and a plurality of blades 45 mounted at intervals along the shaft.
- 15 7. In a muffler, the combination with a casing provided with inlet and outlet passages, of a shaft extending into the casing, a plurality of blades mounted at intervals along the shaft, and means for varying the distance between 50 the blades.
- 20 8. In a muffler, the combination with a casing provided with inlet and outlet passages, of a shaft extending into the casing, means for 55 rotating the shaft, and a plurality of circular series of blades fixed to the shaft.
- 25 9. In a muffler, the combination with a casing provided with inlet and outlet passages, of a rotatable shaft extending into the casing, 60 hubs surrounding the shaft, blades projecting from the hubs, collars interposed between the hubs, and means for forcing the hubs and collars together.
- 30 10. The combination with an elongated casing having near its opposite ends inlet and out- 65

let passages, of a shaft journaled at the ends of the casing and extending therethrough, means for rotating the shaft, and blades mounted upon the shaft at one end of the casing adjacent to the outlet-passage.

40 11. The combination with an elongated casing having near its opposite ends inlet and outlet passages, of a shaft journaled at the ends of the casing and extending therethrough, said shaft being provided between its ends with 45 a fixed collar and a thread at one side thereof, hubs surrounding the shaft, blades projecting from the hubs, and a nut operating upon the threaded portion of the shaft and serving to force the hubs toward the collar.

50 12. The combination with an elongated casing having near its opposite ends inlet and outlet passages, of a shaft journaled at the ends of the casing and extending therethrough, said shaft being provided between its ends with 55 a fixed collar and a thread at one side thereof, hubs surrounding the shaft, blades projecting from the hubs, spacing-collars interposed between the hubs, and a nut operating upon the threaded portion of the shaft and serving to 60 force the hubs and spacing-collars toward the fixed collar.

In testimony whereof I have signed my name to this specification in the presence of two subscribing witnesses.

WILLIAM JOHN HEWITT.
